UNITED STATES PATENT OFFICE.

FREDRICK A. THURSTON, OF LYNN, MASSACHUSETTS.

BUFFING-MACHINE.

1,076,468.

Specification of Letters Patent. Patented Oct. 21, 1913.

Application filed March 7, 1913. Serial No. 752,536.

To all whom it may concern:

Be it known that I, FREDRICK A. THURSTON, a citizen of the United States, residing at Lynn, in the county of Essex and State of Massachusetts, have invented new and useful Improvements in Buffing-Machines, of which the following is a specification.

This invention relates to a machine for buffing articles of sheet material and is especially adapted to buff shoe counters. Said shoe counters are made of different materials, such as leatherboard, and they are hard and difficult to bring to an even beveled edge. They are, therefore, first submitted to a skiving machine which skives off the edge of the article at an angle and then are subsequently run through a buffing machine to still further reduce the edge of the article in thickness and to smooth off the roughnesses left by the skiving machine.

The invention relates particularly to the construction of the roll or movable feed member whereby the counter is held in contact with a sandpaper covered buffing roll also constituting a feed roll.

The invention consists in the combination and arrangement of parts set forth in the following specification and particularly pointed out in the claims.

Referring to the drawings: Figure 1 is an end elevation of a pair of feed rolls embodying my invention, the table upon which the counters are placed preliminary to feeding them between the rolls being shown in section. Fig. 2 is a sectional elevation taken on line 2—2 of Fig. 1 showing a counter in position between the rolls. Fig. 3 is a sectional view taken on line 3—3 of Fig. 2. Fig. 4 is a plan view of the counter after it has been submitted to the buffing operation. Fig. 5 is a section taken on line 5—5 of Fig. 4.

Like numerals refer to like parts throughout the several views of the drawings.

In the drawings, 6 and 7 constitute a pair of feed rolls which are rotated in the direction of the arrows thereon by suitable mechanism. The feed roll 6 is covered with an abrasive material, such as sandpaper 8, and constitutes not only a feed roll but a buffing roll as well.

9 is a table upon which are placed the counters preparatory to feeding them between the feed rolls.

55 The feed roll 7 constitutes a rotary feed member embodying a holder 10 which com-

prises a center piece 11 with segmental blocks 12 fast thereto. These segmental blocks are formed of wood and each has in its outer face a recess 13 adapted to receive a pad 14 of rubber; these pads have vulcanized on their inner faces pieces of textile material 15, such as canvas, and the canvas is fastened by adhesive material to the segmental wooden blocks 12, thus firmly fastening the rubber pads 14 to the segmental blocks 12. There is a space 16 between the inner faces of the pads 14 and the outer surface of the holder or of the wooden blocks 12 forming a portion of said holder. This space 16 extends partly across the feed member 7. When in position it will be seen that the rubber pads 14 are curved on the arc of a circle concentric with the center of the holder 10 and that said rubber pads 14 form the periphery of the feed member 7, they being so constructed and positioned as to engage the periphery of the roll 6.

The roll 6 is held in frictional engagement with the feed member 7 by springs in a manner well known to those skilled in the art. The segmental blocks 12 are detachably fastened to the center piece 11 by screws 17, thus making it possible to replace the blocks when they become worn.

85 The rubber pads 14 are made of softer material on one side thereof than on the other, the part 18 being of substantially softer rubber than the part 19 (see Fig. 2). The object of this construction of the pad is to allow the thick portion of the counter 20 to sink into the pad while the thin "feather" edge of the counter is held firmly against the abrasive surface of the roll 8 during the buffing operation, that is, the end portions 21 of the counter 20 are skived on a skiving machine before the counter is brought to the buffing machine and are skived at an angle or beveled, as seen in Fig. 5, and in the machine of my invention the beveled end 21 is run between the rolls 6 and 7 in order to buff the same. If the rubber pad consisted of rubber of the same resiliency or yielding nature, and that resiliency comparatively stiff, the thick portion of the beveled end of the counter would be forced against the abrasive surface of the roll 6 in such a manner as to cause a shoulder to be cut into the surface of the counter and across the same substantially on the line 22 (Fig. 4); on the other hand if the rubber pads were all of a

100 same resiliency as the pads 14, the thick portion of the beveled end of the counter would be forced against the abrasive surface of the roll 6 in such a manner as to cause a shoulder to be cut into the surface of the counter and across the same substantially on the line 22 (Fig. 4); on the other hand if the rubber pads were all of a

soft rubber the feather edge of the counter would sink into the rubber and not be buffed. It is necessary that the feather edge of the beveled end of the counter should be held up firmly to its work against the buffing roll 6, while the rubber should yield to allow the thick portion of the beveled end to sink thereinto during the buffing operation, and this result is accomplished in such a manner as to leave a straight beveled surface 21 by having the portion 19 made of hard rubber and the portion 18 of soft rubber.

Many of the counters are formed of material which is stiff and unyielding and will not bend laterally thereof so that as one of said counters is fed between the rolls it is desirable that there should be a space 16 between the inner surface of the pad 14 and the outer surface of the portion 12 of the holder 10, so that this space allows the rubber to yield bodily downward as illustrated in Fig. 2 when a counter is passing through between the rolls and thus prevents the buffing roll 6 from cutting into the opposite edges of the counter during the buffing operation. The pad 14 yielding downwardly into the space 16 allows the counter to occupy the space previously occupied by the outer surface of the pad and thus as the counter approaches the roll 6 during the rotation of the feed member 7, the edge of the counter when it first strikes the roll 6 will not be cut into, but will be buffed properly, and the same is true of that edge of the counter which contacts last with the buffing roll 6, the counter conforming, as a whole, substantially to the periphery of the feed member 7 at the thickest portion of said counter. It is unnecessary that any allowance should be made of this nature for the thin end of the counter, but only for that portion adjacent to the line 22 and, therefore, the space 16 is only extended part way across the feed member 7, it being undesirable that there should be a space between the pad and the block 12 beneath the thin end of the counter, for the reason that said thin end must be held firmly up against the buffing roll by the feed member 7 during the buffing operation, or else the buffing roll will have no appreciable effect upon the feather edged end of said counter.

The general operation of the mechanism hereinbefore described is as follows: The counters are placed upon the table 9 in a manner well known to those skilled in the art and fed in between the rolls 6 and 7; the end portion 21 of the counter passing between the rolls 6 and 7 is buffed by the abrasive surface 8 of the roll 6 and is pressed into the soft portion 18 of the rubber pad during this operation, while the soft portion also yields toward the center of the feed member 7 during said operation for

the purpose hereinbefore set forth. The result of the combined yielding of the soft rubber portion 18 of the pad 14 and the bodily yielding downwardly of said rubber is that the portion 21 is buffed evenly and smoothly throughout its entire extent and without any shoulder being cut at its opposite edges between the portion 20 and the portion 21. The counters may pass through a single pair of rolls by reversing the counter end for end, or they may pass through a pair of rolls and the two ends be buffed simultaneously in a manner similar to that illustrated in my Patent No. 1,047,335 of December 17, 1912. When the feed member 7 is first used the periphery or outer surface of the pad 14 projects slightly beyond the outer surface of the block 12, but as the rubber wears away the outer surface thereof becomes concentric with the outer surface of the block 12. After these two surfaces have become even, one with the other, they wear away evenly during the operation of the machine and the roll 6 is kept pressed against the feed member 7 by springs in a manner well known to those skilled in the art as illustrated and described in my said Patent No. 1,047,335.

While I prefer to form the blocks 12 of wood so that they may wear away as the rubber wears by the action of the abrasive material on the surface thereof, still other materials may be used, such as fiber or leatherboard, without departing from the spirit of my invention, so long as said material is non-metallic or of such a nature that it will be worn away as hereinbefore described by the action of the abrasive material thereon.

Having thus described my invention, what I claim and desire by Letters Patent to secure is:

1. A rotary feed member for buffing machines having a yielding pad on its periphery, one portion of which is composed of substantially harder material than the other.
2. A rotary feed member for buffing machines having a yielding pad on its periphery, the portion of said pad at one side of the periphery of said roll being formed of harder material than that portion laterally adjacent thereto on the other side of the periphery of said roll.
3. A rotary feed member for buffing machines having, in combination, a holder with a block fast thereto and a pad fast to said block and curved to form an arc of a circle constituting the periphery of said rotary member.
4. A rotary feed member for buffing machines having, in combination, a holder with a segmental block fast thereto, said block having a recess in its outer face and a pad of rubber located in said recess fast to said block and curved to form an arc of a circle

constituting the periphery of said rotary member.

5. A rotary feed member for buffing machines having, in combination, a holder with 5 a segmental block fast thereto, a pad of rubber curved to form an arc of a circle constituting the periphery of said rotary member and a strip of textile material vulcanized to the inner face of said pad, said 10 textile material fastened by adhesive material to said block.

6. A rotary feed member for buffing machines having, in combination, a holder, a pad of rubber fast to said holder and curved 15 to form an arc of a circle, there being a space extending partly across said holder between the inner surface of said pad and the outer surface of said holder.

7. A buffing machine having, in combination, a pair of feed rolls, one of said rolls 20 covered with abrasive material, the other having a yielding pad on its periphery, a portion of said pad at one side of the pe-

riphery of said roll being formed of harder material than that portion of the pad laterally adjacent thereto on the other side of the periphery of said roll. 25

8. A buffing machine having, in combination, a pair of feed rolls, one of said rolls covered with abrasive material, the other 30 consisting of a holder with a segmental block detachably fastened thereto, said block having a recess in its outer face and a rubber pad located in said recess, said rubber pad being softer on one side thereof than on 35 the side laterally adjacent thereto and there being a space between said rubber pad and block extending partly thereacross.

In testimony whereof I have hereunto set my hand in presence of two subscribing witnesses. 40
